HAIR DRIER

Application filed July 15, 1929. Serial No. 378,470.

This invention relates to beauty parlor equipment, and more especially to an auxiliary attachment for hair dryers.

An object of the invention is the provision 5 of a headpiece adapted for use in beauty parlors and the like, in drying the hair, and in subjecting the scalp and hair to other treatment which involves directing a flow of fluid such as heated or medicated air, onto the patient's head.

Another object is the provision of a device of the general character described, in which means are provided for shielding particular portions of the head of the person 15 being treated, from the blast of fluid.

A more detailed object is the provision of a tubular headpiece adapted to be cooperatively connected to a source of fluid under pressure, such as heated or medicated air, 20 and adapted to be positioned upon the head of the person receiving treatment, and having therein a baffle plate adapted to direct the major portion of the blast away from that portion of the patient's head which is in a direct line with the direction of flow of the blast. An adjustable shield is also provided whereby a portion of the annular space between the baffle and the inner wall of the headpiece, may be either completely closed or partially 25 restricted.

A still further object is the provision of an auxiliary attachment for use in hair drying and analogous uses, which is of a very simple nature, resulting in its economical manufacture and facility of use, and yet which is capable of operating with extreme efficiency in carrying to completion the above enumerated and other objects.

The invention possesses other objects and 35 advantageous features, some of which, with those enumerated, will be set forth in the following description of the invention's particular embodiment which is illustrated in the drawings accompanying and forming a part 40 of the specification.

Referring to the drawings:

Figure 1 is a top plan view of an attachment incorporating the principles of the present invention;

Fig. 2 is a vertical, medial sectional view

taken upon the line 2—2 of Fig. 1, with the direction of view as indicated.

It is common practice in beauty parlors, to dry a person's hair by subjecting the hair to a blast of heated air. This is accomplished ordinarily by the use of a conventional hand blower, or by a headpiece which is adapted to be positioned upon the patient's head, and having a conduit connected thereto whereby heated air is conveyed to the headpiece 55 from a suitable source of supply. An inherent disadvantage of this method, lies in the fact that the crown of the head, lying within the direct line of the blast, receives the major portion of the heated air which, to 60 operate efficiently, must be of such temperature that the direct impingement thereof against the patient's head, is more or less uncomfortable. Particularly true is this in cases where the patient has relatively long 65 hair, inasmuch as the treatment must be continued for a sufficient length of time to dry all the hair, the major portion of which hangs down around the sides and back of the head. Therefore, before the side and back hair can 70 be efficiently dried, the relatively thin hair at the top of the head, has already become dry, and the continued direction of the blast of heated air thereagainst, soon becomes uncomfortable to the patient. Furthermore, 75

the patient derives discomfort from the flow of heated air downwards about the face. It is with these undesirable characteristics of previously existing beauty parlor equipment in mind, that I have produced the improved 80 auxiliary attachment of the present invention which is designed to overcome them, and yield a device which is capable of operating efficiently, and still eliminate any inconvenience or discomfort to the patient.

Specifically describing the invention in its most practical embodiment of which I am at present aware, the drying device comprises a tubular headpiece indicated in its entirety at 6, preferably circular in cross section, and 85 open at both ends. The upper portion 7 of the headpiece 6, preferably flares slightly toward the bottom, and receives a substantially cylindrical portion 8 of suitable diameter, to be received upon the head of the 90

patient receiving treatment. In Fig. 2, the contour of the patient's head, is indicated in dashed lines as at 9, to show the manner of employment of the device.

- 5 Means are provided at the top of the head-piece 6, for attaching a suitable conduit 11 thereto, whereby such fluid as heated or medicated air, may be conveyed from a suitable source to the interior of the headpiece 6.
- 10 While any convenient type of conduit 11 may be employed, that disclosed upon Fig. 2, is of flexible material; and a convenient method of attachment therefor, comprises a resilient ring 12 adapted to press the lower 15 edge of the conduit 11 outwards against the inner circumference of the upper end of the portion 7 of the headpiece 6. A bead 13 is formed at the extreme upper end, forming a groove 14 on the inner circumference, with- 20 in which the ring 12 is adapted to firmly press the material of the conduit 11, as a result of its inherent expansive resiliency. It will be readily understood that if a different type of conduit 11 is employed, the 25 means of attachment thereof to the headpiece 6, may be suitably varied so as to accommodate whatever type of conduit 11 is to be connected thereto.

A conical baffle 16 is disposed coaxially 30 within the headpiece 6, being positioned with its apex 17, which is preferably rounded, directed upwards, and with its base 18 spaced from the inside wall of the headpiece 6, thus defining an annular space 19 between the 35 inner circumference of the headpiece 6 and the portion of largest diameter of the baffle 16. The baffle 16 is retained rigidly in position through the expedient of a plurality of ribs 21 soldered or otherwise firmly attached to 40 both the inside of the headpiece 6 and the outside of the baffle 16. The parts are so proportioned and arranged that when the headpiece 6 is positioned upon a patient's head 9, the base 18 of the baffle, is only slightly 45 above the crown of the patient's head, as clearly indicated upon Fig. 2.

A deflector 22 is rigidly mounted inside the headpiece 6 at that portion thereof which is to be positioned above the front of the 50 patient's head. This deflector is preferably permanently attached to both the inside of the headpiece 6 and the outside of the baffle 16, for which purpose a suitable flange 23 may be formed at the inner edge of the de- 55 flector 22, to facilitate soldering or whatever method of attachment is employed. The under face of the deflector 22, is concave, and the adjacent portion of the base 18 of the baffle 16, is rounded to conform to the con- 60 figuration of the deflector 22, as indicated at 24.

A slot 26 is formed in the headpiece 6, this slot extending throughout substantially one-half the circumference thereof, and having 65 its central portion preferably disposed above

the center of the deflector 22. Furthermore, the slot 26 is preferably arranged at an incline so that its ends are considerably lower than its central portion, as clearly indicated upon Fig. 2. Extending angularly upwards 70 from the headpiece 6 within the plane of the slot 26, is a guide 27 in the form of opposed spaced plates 28, soldered or otherwise firmly attached to the outside of the headpiece 6, upon each side of the slot 26. The opposed 75 side edges of at least one of the plates 28, are bent to permit their being attached to the other plate, so as to completely enclose the slot 26. The outer ends 29 of the plates, instead of being joined, are bent back upon 80 themselves as a provision to increase the inherent strength of the structure, and to leave the outermost end of the guide 27 open for the reception of a shield 31 which is slidably mounted between the two plates 28. The outermost edge 32 of the shield 31, is deflected 85 to provide a flange, thus affording a better finger grip to facilitate adjustment of the shield; and the parts are so proportioned and arranged that when the shield 31 is 90 pushed to its innermost extreme of movement wherein the flange 32 engages the outermost edge of one of the plates 28, the inner edge 33 of the shield 31, is disposed 95 substantially diametrically of the headpiece 6, as shown upon Fig. 1. Accordingly, a notch 34 is formed in the inner edge 33, permitting the edge 33 to conform to the engaged portion of the conical baffle 16.

A clamping screw 36 extends loosely 100 through one of the plates 28, and is threaded into the other. This screw extends through a slot 37 formed in the shield 31 and extending parallel to the side edges thereof; with the result that the shield 31 may be slid outwards within its guide 27, from the position indicated upon the figures, to that position in which it is completely withdrawn from the interior of the headpiece 6, or any position intermediate these two extremes. As a result, the shield is adapted to have its effective area varied so as to optionally restrict or completely close the space inside the headpiece and on one side of the baffle. After the shield 31 has been moved to desired position, the clamping screw 36 may be tightened to press the plates 28 firmly thereagainst and hold the shield 31 as adjusted.

The manner of operation of the attachment of the present invention is believed obvious from the above description of its constituent parts. After the conduit 11 has been suitably attached, and the device positioned upon the head 9 of the patient, the air blast should be started. The current of air will thus be directed downwards upon the patient's head. However, the baffle 16 will direct the major portion of the air toward the back and sides of the head, so that the crown of the head where the hair is thinnest, will not receive the 105 110 115 120 125 130

direct action of the blast, and result in the thicker portions of the hair receiving the major portion of the air blast. Furthermore, the deflector 22 will prevent the heated air from striking the patient's face. If, as the treatment continues, it is found that the hair at the front of the head, is becoming dry more rapidly than the remaining portions, the shield 31 may be slid inwards as far as deemed advisable, to properly regulate the rapidity of the drying operation over the entire surface of the head. Obviously, the entire headpiece 6 may be twisted from side to side to control the blast of air accordingly.

It is to be understood that the details of the invention as herein disclosed, are subject to alteration within the spirit or scope of the appended claims.

20 I claim:

1. A device of the character described, comprising a tubular headpiece open at its lower end and adapted to be positioned upon a patient's head, means for coupling a source of fluid under pressure to said headpiece, and a slidably adjustable shield disposed within the headpiece to protect selected portions of the patient's head from said fluid.

2. A device of the character described, comprising a tubular headpiece open at its lower end and adapted to be positioned upon a patient's head, means for coupling a source of fluid under pressure to said headpiece, a shield disposed within the headpiece to protect selected portions of the patient's head from said fluid, said shield being adjustable to permit varying the effective area of said shield.

3. A device of the character described, comprising a tubular headpiece open at its lower end and adapted to be positioned upon a patient's head, means for coupling a source of fluid under pressure to said headpiece, and a rigid conical baffle arranged coaxially within said headpiece and extending to a position adjacent to the top of the patient's head.

4. A device of the character described, comprising a tubular headpiece open at its lower end and adapted to be positioned upon a patient's head, means for coupling a source of fluid under pressure to said headpiece, and a rigid conical baffle arranged coaxially within said headpiece, the apex of said baffle being directed upwards and its base being spaced from the inside wall of said headpiece and extending to a position adjacent to the top of the patient's head.

5. A device of the character described, comprising a tubular headpiece open at its lower end and adapted to be positioned upon a patient's head, means for coupling a source of fluid under pressure to said headpiece, a rigid conical baffle arranged coaxially within said headpiece, the apex of said baffle being directed upwards and its base being

spaced from the inside wall of said headpiece, and a deflector closing a portion of the annular space between the base of said baffle and the headpiece.

6. A device of the character described, comprising a tubular headpiece open at its lower end and adapted to be positioned upon a patient's head, means for coupling a source of fluid under pressure to said headpiece, a rigid conical baffle arranged coaxially within said headpiece, the apex of said baffle being directed upwards and its base being spaced from the inside wall of said headpiece, and a deflector closing a portion of the annular space between the base of said baffle and the headpiece, the inner face of said deflector being concave to conform to the adjacent portion of the patient's head.

7. A device of the character described, comprising a tubular headpiece open at its lower end and adapted to be positioned upon a patient's head, means for coupling a source of fluid under pressure to said headpiece, and a shield adjustable to optionally restrict or completely close the space inside the headpiece and on one side of the baffle.

8. A device of the character described, comprising a tubular headpiece open at its lower end and adapted to be fitted upon a patient's head, means for coupling a source of fluid under pressure to said headpiece, a guide extending from the headpiece and enclosing a slot therein, and a shield slidable within said guide and extending through said slot.

9. A device of the character described, comprising a tubular headpiece open at its lower end and adapted to be positioned upon a patient's head, means for coupling a source of fluid under pressure to said headpiece, a guide extending from the headpiece and enclosing a slot therein, said slot extending throughout one-half the circumference of said headpiece, and a shield slidable within said guide and extending through said slot.

10. A device of the character described, comprising a tubular headpiece open at its lower end and adapted to be positioned upon a patient's head, means for coupling a source of fluid under pressure to said headpiece, a guide extending angularly upwards from the headpiece and enclosing a slot therein, said slot extending throughout one-half the circumference of said headpiece, and a shield slidable within said guide and extending through said slot.

11. A device of the character described, comprising a tubular headpiece open at its lower end and adapted to be positioned upon a patient's head, means for coupling a source of fluid under pressure to said headpiece, a guide extending angularly upwards from the headpiece and enclosing a slot therein, said slot extending throughout one-half the circumference of said headpiece, a shield

slidable within said guide and extending through said slot, and means for clamping said shield in selected position.

12. A device of the character described, comprising a tubular headpiece open at its lower end and adapted to be positioned upon a patient's head, means for coupling a source of fluid under pressure to said headpiece, a guide extending angularly upwards from the headpiece and enclosing a slot therein, said slot extending throughout one-half the circumference of said headpiece, a shield slidable within said guide and extending through said slot, the inner edge of said shield being adapted to engage the baffle and being shaped to conform thereto, and means for clamping said shield in selected position.

In testimony whereof I have signed my name to this specification.
